UNITED STATES PATENT OFFICE.

WILLIAM F. SENTER, OF MARSHALL, MISSOURI.

MARKING AND DROPPING ATTACHMENT FOR PLANTERS.

SPECIFICATION forming part of Letters Patent No. 225,426, dated March 9, 1880.

Application filed August 21, 1879.

To all whom it may concern:

Be it known that I, WILLIAM F. SENTER, of Marshall, in the county of Salem and State of Missouri, have invented a new and valuable Improvement in Marking and Dropping Attachments for Planters; and I do hereby declare that the following is a full, clear, and exact description of the construction and operation of the same, reference being had to the annexed drawings, making a part of this specification, and to the letters and figures of reference marked thereon.

Figure 1 of the drawings is a representation of longitudinal central vertical section of my invention. Fig. 2 is a top view of the same, and Fig. 3 is a detail.

This invention has relation to improvements in marking and dropping attachments for corn-planters; and the nature of the invention consists in certain novel arrangements and combinations of devices whereby important results are obtained, as will be hereinafter more fully set forth.

In the accompanying drawings, the letter A designates the usual runners of a corn-planter, carrying the seed-hoppers A' at its ends, and provided with the usual dropper-slide B. Connecting the runners in front and rear are the beams a a', to which is bolted the draft-bar b, carrying on its front end a vertically-swinging tongue.

The runner-frame is connected pivotally to the axle of the transporting and covering wheels B' by means of the reach-rods b', and the bar B², supporting the driver's seat, is bolted to said axle and pivoted to said frame, so as not to interfere with the vertical movements of the latter. These features are old and well known, and no claim is made thereto. Erected on the bar b, in front of the beam a and overhanging the same, is a bracket, c, between which and said beam is journaled the horizontally-vibrating bolster C, having in its enlarged middle part a slot, s. Extending endwise through this bolster is a metallic shaft, c', upon which is journaled a cam, d, and sprocket or chain wheel d', inside of slot s, the cam and wheel being made in one piece usually, or coupled together in any suitable way. The ends of shaft c' project beyond the ends of the bolster, forming journals e, upon which

the front ends of the side bars, f, of the marker-frame D have their bearings, and upon which the said frame vibrates vertically. The cam d has in its perimeter two grooves, i, the major parts of which are parallel to each other, but which cross each other at one point at an angle of about forty-five degrees, presenting at the point of intersection the form of the letter X. This double cam operates a lever, E, having its fulcrum on a spindle on the draw-bar and pivoted to the dropper-slide. This lever has pivoted to its end a double-convex traveler, j, moving freely in grooves i, and passing readily at the intersection of said grooves from the one to the other, thus imparting to lever E at the moment of passing the junction of the cam-grooves a rapid vibration, and to the slide a correspondingly quick reciprocation.

The frame D is suitably braced transversely by the bars h and longitudinally by the bars h'. To the side bars and braces h are secured the bars l, extending out beyond the sides of the frame D a sufficient distance, and affording bearings to a shaft, F, upon the ends of which are keyed or otherwise secured the hubs l', having projecting spokes l'', provided alternately with long and short feet m m'.

The marker-wheels thus described, and designated by the letter G, actuate, by means of an endless chain, G', passing around chain-wheel d', and a larger chain-wheel, d'', upon the shaft of the marker-wheels G, the dropper-slide aforesaid, and thereby deliver the seed at proper intervals. The feet m m' are angular in cross-section and make clearly-marked impressions in the soil of different lengths, the longest impressions being those in which the seed is dropped, and the short ones being merely to create a distinction at the end of the row and indicate how a start should be made thereat. Connected to the shaft of the marker-wheels by means of a link, k, is a lever, H, having its fulcrum in uprights on the axle of the transporting-wheels and extending to the rear under the driver's seat. By forcing this lever downward the said shaft is thrown upward, raising the marking-feet out of the ground, when, by the employment of a vibrating prop, I, pivoted to said uprights, the said wheels and frame are retained in a raised po-

sition by engaging said prop with the rear cross-bar of the latter.

By raising the runners by the usual means the apparatus may be driven from place to place or turned at the end of the row without actuating the dropper.

J' indicates a vertically-vibrating lever pivoted to the front bar of the frame of the marker and having both vertical and horizontal vibration. This lever extends to the rear within convenient reach of the driver, and is provided with a rigid projecting arm, t, extending across the face of the wheel d², but not in contact therewith, except when the lever is thrown to the right, when the enlarged end of said arm passes between the teeth of the said wheel and locks it against further movement. On the under side of this lever is a pivoted arm, z, the extremity of which is held in contact with the wheel, or nearly so, by a spring, s'. The marking-feet being raised, as above described, off the ground, the driver can, at the end of the rows, by operating this lever, bring the desired foot directly over the mark in the soil on either side, and then lower the wheels until the foot drops into it, when by starting the team the corn or seed will drop precisely in line with the hills already planted.

The distance between the middle of the lengths of the feet on opposite sides of the

apparatus is precisely the same as the space included between three adjoining rows. Consequently the marks are midway between the last row planted and that adjacent thereto being planted on one side and the other row being planted and the first row of the next crossing, and each wheel steps back in its own tracks every crossing except the first. The lateral play of the marker-frame allows the planter to swerve or turn without throwing out the marking blades or feet.

What I claim as new, and desire to secure by Letters Patent, is—

The combination, with a planter having the horizontally-vibrating bolster C, a shaft, c', 45 extending through it endwise, and a cam, d, operating the dropper, and a chain-wheel, d', arranged on said shaft in a slot of the bolster, of the frame D, the shaft F, carrying the chain-wheel d² and marker-wheels G, and pivoted to 50 the ends of shaft c', and an endless chain passing around wheels d' d², substantially as specified.

In testimony that I claim the above I have hereunto subscribed my name in the presence of two witnesses.

WILLIAM F. SENTER.
